UNITED STATES PATENT OFFICE.

WILLIAM BRYANT MOORE, OF NEW BOSTON, TEXAS.

FOLDING TABLE.

SPECIFICATION forming part of Letters Patent No. 782,161, dated February 7, 1905.

Application filed July 25, 1904. Serial No. 217,992.

To all whom it may concern:

Be it known that I, WILLIAM BRYANT MOORE, a citizen of the United States, residing at New Boston, in the county of Bowie and State of Texas, have invented certain new and useful Improvements in Folding Tables; and I do declare the following to be a full, clear, and exact description of the invention, such as will enable others skilled in the art to which it applies to make and use the same.

My invention relates to folding tables; and one of the objects of the same is to provide a table with means under the top or leaves for containing certain articles for table use or for provisions and to hinge the two halves of the table together in a manner to render them available as a closed cupboard or container for table articles.

Another object of my invention is to provide a table with receptacles or compartments under the leaves or table-top for containing folding legs for the table and to provide compartments for a variety of articles, the two halves of the table adapted to be closed together and locked to form a closed compartment which will occupy but small space compared to an ordinary dining-table.

These and other objects are attained by means of the construction illustrated in the accompanying drawings, in which—

Figure 1 is a perspective view of the table with the hinged or pivoted legs in position to support same. Fig. 2 is an under side plan view of the table. Fig. 3 is a perspective view of the table when folded, and Fig. 4 is a front view of the under side of the table when one of the hinged compartments is supported against the side wall.

Referring to the drawings for a more particular description of my invention, the numerals 1 1^a designate the two leaves or top of the table. Underneath each of the leaves or top two square box-like receptacles 2 2^a are provided, and the hinges for connecting the two halves of the table are secured to the lower edges of the contiguous sides of these compartments. The legs 3 are each pivoted upon a pin 4, extending through the side walls of the compartment, through the leg, and into a bearing-block 5, secured within the com-

partment to the end wall thereof, as shown. In order that the legs may fold within a comparatively small space, they are provided with opposite bevels 6. When the legs are folded down within the compartment, they occupy 55 but little space laterally of said compartment. When the legs are thrown out in position to support the table, they are held in this position by means of a spring-keeper 7, secured by staples 8 underneath the lid or top of the 60 table, as shown, said keeper being adapted to be sprung in place to bear against the inner sides of the legs to hold them in place in an obvious manner.

A series of receptacles or boxes extending 65 from end to end of one of the compartments and provided with suitable partitions may be used for containing condiments, spices, and other articles for table use.

To insure a rigid connection of the two tops 70 or leaves when the table is extended a bolt 8 is mounted in a keeper 9, secured at one end of one of the compartments and adapted to be extended into a keeper 10 upon the opposite leaf or top. The keeper 9 may be a piece of 75 sheet metal of the required thickness bent into Z shape, as shown, and secured in place by a number of small screws passing outward into the table-top. A slot 11 is formed in one portion of the keeper, and a stud 12 passes through 80 the slot and is connected to the bolt 8.

Within one of the compartments is provided a plate-rack 19, comprising a series of strips 14 and supports 15 at the bottom for plates, cups, saucers, and other table-service ware. 85 Compartments may also be provided for knives, forks, spoons, &c.

When it is desired to fold the table and put away the table-service, the legs of the table may be folded inward and the table reversed 90 into position, one leaf of the table being supported against the side wall, as shown in Fig. 4. If, however, it is desired to entirely close the table, the two halves may be swung together and held in this position by means of 95 the latches 16. Handles 17 may be provided for lifting the table when closed, and a suitable lock may also be provided, if found desirable.

From the foregoing it will be obvious that a folded table made in accordance with my in- 100

vention will be found very desirable, particularly in places where room is scarce and where closet-room or pantry-space is not to be had. When folded, the table occupies very little 5 room and serves to keep out of sight the articles necessary for table - service, while the table may be readily opened and the articles made accessible with but little trouble.

Having thus described my invention, what 10 I claim as new, and desire to secure by Letters Patent, is—

15 A folding table comprising two leaves forming the top of the table, compartments under the leaves, the contiguous sides of said compartments being flush with the contiguous edges of the leaves, hinges secured to the bottom edges of the contiguous sides of said compartments, legs pivoted to fold within said

compartments, spring-keepers for holding the legs in extended position, a square sliding 20 bolt for holding the leaves in extended position, the casing for said bolt being substantially Z-shaped in cross-section and secured under one of the leaves at one end of one of the compartments, one edge of said keeper 25 lying against said end of the compartment, and a pin forming a keeper under the opposite leaf of the table, substantially as described.

In testimony whereof I have hereunto set my hand in presence of two subscribing witnesses. 30

WILLIAM BRYANT MOORE.
